SOLENOID OPERATED CAN OPENER
Hilton H. Eady, Rte. 1, Franklin, Ga., assignor of fifty
percent to James N. Register, Warner Robins, Ga.
Filed May 3, 1960, Ser. No. 26,614
4 Claims. (Cl. 30—4)

The present invention generally relates to a can opener and more particularly to such a can opener which is solenoid operated in response to insertion of a can into position for engagement by the opener.

It is present day practice to package many liquids in puncturable cans. Such canned materials include beer, carbonated beverages, fruit juices and the like. Beer and carbonated beverages quite often are sold over the counter for consumption at a relatively high volume rate. There have been hand operated punch devices for opening the containers or cans in which it has been necessary to puncture two openings in the top of the can, one for discharging the liquid and one for admitting air to replace the discharged liquid. This manual operation is quite time consuming and laborious especially where a large number of containers must be opened in a relatively short period of time. Therefore, it is the primary object of the present invention to provide an automatically operated can opener which will open a can automatically when the can is placed in position in alignment with the punch or cutter mounted on the machine thereby automatically opening the can with the machine including the cutter or punch automatically returning to a position for receiving a subsequent container when the opened container has been removed.

Another important object of the present invention is to provide a can opener in accordance with the preceding object which is actuated by a solenoid having a micro-switch engageable by the container for automatically operating the solenoid when the container to be opened is placed in position for receiving the cutter or punch for forming the opening in the top of the can.

A further important object of the present invention is to provide a can opener that is automatically operated in accordance with the preceding objects, the can opener being adjustable for receiving and opening different heights and sizes of containers.

Still another important feature of the present invention is to provide an automatic solenoid operated can opener which is simple in construction, easy to use, effective for its particular purposes, foolproof, long lasting, adjustable and relatively inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a side elevational view of the can opener of the present invention illustrating the device in a lowered condition for opening small cans;

FIGURE 2 is a side elevational view of the construction of FIGURE 1 but with the can opener adjusted for receiving larger cans;

FIGURE 3 is a front view of the construction of FIGURE 1;

FIGURE 4 is a top plan view of the can opener;

FIGURE 5 is a transverse, sectional view taken substantially upon a plane passing along section line 5—5 of FIGURE 1 illustrating the structural details of the invention;

FIGURE 6 is a front view of another type of cutter which may be employed with the can opener;

FIGURE 7 is a side elevational view of the cutter or punch of FIGURE 6; and

2

FIGURE 8 is a perspective view of a guide plate employed for receiving the container and centralizing it in relation to the can opener.

Referring now specifically to the drawings, the numeral 5 generally designates the can opener of the present invention that includes a vertically adjustable working head generally designated by the numeral 12.

The can opener 10 includes a base plate 14 having an upstanding standard 16 adjacent one end thereof with the standard 16 preferably being square and rigidly secured to the plate. A gusset 18 extends from the rear edge of the standard 16 to the upper surface of the plate 14 for further rigidifying the standard 16. The standard 16 also is provided with a collar 20 at the upper end 15 of the gusset 18 which forms a seat for one end of a compression coil spring 22 which acts as a support for the working head 12 for permitting the working head 12 to slide on the standard 16 and normally biasing the working head 12 to an upper position.

20 Mounted on the upper end portion of the standard 16 is a generally U-shaped adjusting member designated generally by the numeral 24 which includes a bight portion 26, a short leg 28 having a rounded end 30 and a longer leg 32 in spaced parallel relation to the short leg 25. The corner of the adjuster 24 defined by the juncture between the bight portion 26 and the short leg 28 is pivotally attached to the standard 16 as by a pivot pin 34. The free end of the leg 32 is pivotally attached to an elongated link 36 as by pivot pin 38. The link 36 30 extends downwardly and outwardly towards one side edge of the base plate 14 where it is pivotally attached to an operating handle 40 by virtue of a pivot pin 42. The operating handle 40 is elongated and is disposed alongside of the base plate 14 with one end thereof pivotally attached to an upstanding lug 44 at the rear corner of the base plate 14 by virtue of a pivot pin 46. The other end of the handle 40 is provided with a knob 48 thereon for facilitating pivotal movement of the handle 40. All 35 of the pivotal pin connections may be in the form of 40 pivot bolts, rivets or the like.

The adjuster 24 is pivoted about the axis of the pin 34 when the handle 40 is swung about the axis of the pivot pin 46. This will move the U-shaped adjuster 24 from the position illustrated in FIGURE 1 to the position 45 illustrated in FIGURE 2. The rounded end 30 of the leg 28 engages the working head 12 when the leg 28 is in alignment with and alongside of the standard 16 thus retaining the working head 12 in a depressed or lowered position. When the U-shaped adjuster 24 is rotated to a 50 position with the leg 28 perpendicular to the standard 16 as illustrated in FIGURE 2, the spring 22 will urge the cutting head 12 upwardly against the outer edge of the leg 28 thus retaining the cutter head in an upper position. When the cutter head is in a lowered position, it is 55 adapted to open short tin cans or containers 50 and while it is in its upper position, it is adjusted for opening taller tin cans or containers also designated by the reference numeral 50.

The cutter head 12 includes a vertically disposed 60 transversely extending mounting plate 52 to which is rigidly attached a U-shaped sleeve 54 which cooperates with the plate 52 to provide a sleeve encircling and slidably receiving the standard 16 thus slidably mounting the plate 52 in relation to the standard 16. The upper end edge of the leg of the U-shaped sleeve 54 which engages the leg 28 of the adjuster 24 is laterally elongated as indicated by the numeral 56 to provide bearing engagement with the elongated edge of the leg 28 and also forming engagement with the rounded end 65 30 whereby effective connection will be maintained between the adjuster 24 and the sleeve defined by the U-shaped member 54 and the mounting plate 52.

Attached to the vertical end edges of the mounting plate 52 is a pair of inwardly facing U-shaped or channel-shaped brackets 58 attached to the mounting plate 52 by bolts 60 or other equivalent fastening means. Each of the U-shaped brackets 58 extend substantially throughout the length of the mounting plate 52 with the upper end thereof being flush with the upper edge of the mounting plate 52. The forward corner portion of each of the brackets 58 project downwardly in the form of an angle iron extension 62 which are disposed parallel to the standard 16 and the lower ends of the extensions 62 are interconnected by a guide member generally designated by numeral 64 which includes a vertical flange 66 having apertures 68 therein for receiving screw threaded fasteners 70 thereby securing the ends of the flange 66 to the extensions 62. The lower edge of the flange 66 is provided with a horizontal flange 72 having an arcuate notch 74 formed therein for engagement with the container or can 50 thus guiding and positioning the can when it is placed into the can opener.

The portion of the brackets 58 coextensive with the mounting plate 52 is provided with a solenoid generally designated by the numeral 76 which includes a main body 78 secured in position by angle iron brackets 80 and elongated fastening bolts 82 which extend through the inwardly extending flanges of the U-shaped brackets 58 thus mounting the solenoid rigidly in relation to the mounting plate 52. The solenoid 76 includes the usual winding 84 and a movable core or plunger 86 slideable longitudinally therethrough so that the plunger 86 will be moved downwardly when the winding 84 is energized in a well known manner. The upper end of the core or plunger 86 is provided with a lateral enlargement 88 to limit the downward movement of the core or plunger 86.

Mounted alongside of and outwardly of the upper end of each of the brackets 54 is a spring supporting rod 90 rigid with the mounting plate 52 and rigid with the brackets 58. The rods 90 engage and support the upper end of a tension coil spring 92. The lower end of the spring 92 is connected to apertured ends of a transverse strap member 94 which has a central vertical portion 96 attached to the lower end of the plunger 86 by screw threaded fasteners 98. The screw threaded fasteners 98 also extend through apertures 100 in a cutter or punch generally designated by the numeral 101. The punch 101 is provided with an inclined lower surface 102 and converging front surfaces 104 cooperating to form a vertical edge 106 and a point 108 which will puncture substantially a triangular shaped opening in a container. The edge of the punch opposite from the vertical edge 106 is rounded as indicated by the numeral 110 to conform generally to the curvature of the container to be opened. Further, the punch or cutter 101 is provided with a recess 112 in the upper edge thereof with the apertures 100 being formed in the recess 112 and with the plate or strap 94 and the enlargement 96 thereon being received also in the recess 112 thus rigidly securing the transverse strap 94 to the punch or cutter 101 and also to the plunger 86 for movement therewith. When the plunger 86 is forced downwardly by energizing the solenoid, the springs 92 will retract the punch from the container so that the punch will then be ready for a subsequent punching or opening operation.

For energizing the solenoid, electrical conductors 114 are provided and are connected with a suitable male plug 116 for connection to a conventional household current outlet. One of the conductors 114 is provided with a microswitch 118 for normally retaining the circuit to the solenoid open. The microswitch 118 is provided with an actuating plunger 120 disposed for engagement by the lower end of the container or can 50 when it is placed in position against the guide 64. Thus, as the container 50

closes the switch 118, the solenoid will be operated. By moving the can or container 50 slightly away from the microswitch 118, then the solenoid will be deenergized whereby the springs 92 will retract the punch or cutter from the can 50 so that the can may be fully removed and a subsequent can placed in position. The microswitch 118 is mounted on the base plate 14 in any suitable manner and there are also provided a pair of converging L-shaped guide members 122 secured to the base plate 14 by fastening bolts 124 which form generally a pair of converging surfaces for guiding the can or container 50 into position for engagement with the microswitch plunger 120.

The present invention will operate successfully with only one larger cutter which will form an opening in the container sufficiently large that it will not need an air vent. However, if desired, a pair of smaller cutters may be attached to the lower end of the plunger in lieu of the single enlarged cutter thus simultaneously providing two holes or openings in the upper end of the container. The two smaller openers or cutters may be adjustably mounted for engagement with different size containers.

Briefly, in operation, the working head 12 will be adjusted to open either small or tall cans as illustrated in FIGURES 1 and 2 and the container 50 is then placed in position against the guide 64 and the lower end of the container 50 will engage the microswitch thus closing the circuit to the solenoid and causing the plunger and the cutter or punch mounted thereon to move downwardly for opening the container in an obvious manner. After the opening operation, the container 50 may be moved slightly away from the microswitch at the bottom thus allowing the microswitch to open the circuit and de-energize the solenoid whereby the solenoid plunger will be retracted to an uppermost position and removed from the top of the container.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A can opener comprising a base, an upstanding standard rigid with said base, a can opener head slidably mounted on said standard for varying the vertical position thereof, said head including a solenoid having a vertically movable core, can opening means mounted on the lower end of the core for opening the top of a can when the core is forced downwardly when the solenoid is energized, and switch means mounted on the base, said switch means being disposed in an electrical circuit for the solenoid and normally being open for retaining the solenoid in deenergized condition, said switch means including an operating member disposed for engagement by the can when placed on the base thus closing the circuit and energizing the solenoid for automatically opening the can, said plunger in the switch being spring biased to an open position when the can is moved away from the switch thus deenergizing the solenoid, said solenoid including spring means interconnecting the core and the body thereof for retracting the core when the solenoid is deenergized, manually operated lever means connected between said head and said base for manually operating said head vertically and selectively manually locking it in one of a plurality of vertically spaced positions.

2. A can opener comprising a base, an upstanding standard rigid with said base, a can opener head slidably mounted on said standard for varying the vertical position thereof, said head including a solenoid having a vertically movable core, can opening means mounted on the lower end of the core for opening the top of a can

when the core is forced downwardly when the solenoid is energized, and switch means mounted on the base, said switch means being disposed in an electrical circuit for the solenoid and normally being open for retaining the solenoid in deenergized condition, said switch means including an operating plunger disposed for engagement by the can when placed on the base thus closing the circuit and energizing the solenoid for automatically opening the can, said plunger in the switch being spring biased to an open position when the can is moved away from the switch thus deenergizing the solenoid, said solenoid including spring means interconnecting the core and the body thereof for retracting the core when the solenoid is deenergized, said head including a sleeve slidably engaging the standard, spring means biasing the sleeve upwardly, and other means mounted on the standard and engaged with the upper end portion of the sleeve for forcing the sleeve downward to a lowered position or permitting the sleeve to move up-

15

10

20

ward to an upper position for receiving different heights of containers under the solenoid.

3. The structure as defined in claim 2 wherein said sleeve is provided with depending members supporting the transversely arcuated guide for positioning the containers in position for engagement by the can opening means on the lower end of the core of the solenoid.

4. The combination of claim 3 wherein said other means on said standard engaged with the upper end portion of the sleeve includes a U-shaped adjuster having one bight corner pivotally attached to the standard, and a handle member pivotally attached to the base, a link interconnecting the handle and adjuster for operating the adjuster.
